ELECTROMAGNETIC ACTUATOR

Owen L. Taylor, Easton, Conn., assignor to Westinghouse Electric Corporation, East Pittsburgh, Pa., a corporation of Pennsylvania

Application March 6, 1953, Serial No. 340,859

7 Claims. (Cl. 317—198)

This invention relates to electric circuit controlling devices and more particularly, to electromagnetically-operated switches.

The assembly of the magnet and related parts of electromagnetically-operated switches of the type referred to herein should be such that the switch will be quiet and develop the necessary force-travel relationship. The assembly should allow easy access to and removal of the operating coil and a minimum number of parts to remove and handle. The moving parts should be of such a design as to insure long operating life.

The quietness of operation and the operating life of A. C. magnets are contingent upon alignment of the seating pole faces of the armature and magnet, and upon the proper loading of the armature, as well as proper shading. The above factors are dependent upon the proper mounting of the armature. If the magnet and the armature pole faces are properly ground so that a large proportion of these faces are in practical contact when the armature is free, the only problem of alignment is to have the armature mounted in such a manner as to assume this position when mounted in its supporting member and when seated. A movement about any axis parallel to the pole faces of the armature tends to make the device noisy at much lower force values than when a load is applied to the armature along an axis perpendicular to the plane of the pole faces and through the theoretical center area of all pole faces in combination (this center does not necessarily fall within any of the actual seating areas). A load applied in such a manner is referred to as a balanced load.

Prior art methods of mounting armatures have two major drawbacks. First, the free floating armature allows movement of the armature about its bearing parts with resultant wear in the armature mounting assembly. Second, there is no control over the movement of the armature until the armature is seated. Due to magnetic forces involved one pole face will always make contact before the other and the resultant relative movement in the area of contact of the pole faces induces wear on the pole face area.

It is an object of this invention to provide a circuit controlling device of the character referred to which obviates the defects of the prior art devices and provides the requisite features.

Another object of this invention is to provide a circuit controlling device of the electromagnetically-operated type having the load applied to the armature along an axis perpendicular to the plane of the pole faces and substantially through the theoretical center area of all pole faces.

A further object of this invention is to provide a circuit controlling device of the electromagnetic type such that the armature pole faces may be aligned with the magnet pole faces to give a balanced load condition and the armature pole faces are held in alignment with the magnet pole faces for any condition of the circuit controlling device.

Still another object of this invention is to provide a circuit controlling device of the electromagnetically-operated type which is quiet in operation, develops the necessary force-travel relationship, is easy to assemble, has a

2

minimum number of operating parts and is positive in action.

The objects recited are merely illustrative. Other objects and advantages will become more apparent from a study of the accompanying figures, in which:

Figure 1 shows a front view of the assembled electromagnetic contactor;

Fig. 2 shows a side view of the assembled electromagnetic contactor;

Figs. 3, 4 and 5 show details of the armature and the armature bracket;

Fig. 6 shows the parallelogram arrangement through which motion is transmitted from the armature to the contact actuating means; and

Figs. 7 and 8 show details of the parallelogram arrangement.

With specific reference to the form of the invention as illustrated in Figs. 1 and 2, a base plate 2 is provided with extended portions 3 and 4. The extended portions

3 have holes therein for receiving a bolt to fix the base plate of the relay to a panelboard. A resilient member 5, as, for example, a rubber grommet, is provided on the back of the base plate so that the extended portions 3 and 4 and the resilient member 5 which give a snug fit with a panelboard when the contactor is fixed thereto and permits positive mounting with only two mounting screws or bolts on surfaces which may not be perfectly flat. The resilient member 5 also absorbs the shock from the closing action of the contactor.

Contact support means 6, which supports fixed contact members, a bearing bracket 7, and an electromagnet bracket 8, are attached to the base plate 2 in any suitable manner. The electromagnet bracket 8 is comprised of two metallic members which fit on each side of the laminated electromagnet core 1 and hold the laminations together. A portion of each metallic member extends perpendicular to the plane of the laminations and away from the core 1 so that the metallic members may be fixed to the base plate and thus hold the core 1 in position.

A coil 9 is provided on the center leg of the E-shaped electromagnet. The bearing bracket 7 is one of four plates which form a parallelogram arrangement. The bearing bracket 7 has bearing surfaces at each end which are engaged by bearing edges of upper rocker arm

10 and the lower rocker arm 11, respectively. The opposite bearing edge of the upper rocker arm 10 engages a bearing surface of the armature bracket 12 and the bearing edge at the opposite end of the lower rocker arm 11 engages the lower bearing surface of the armature bracket 12. The armature bracket 12 has a bolt 13 projecting through two extensions on the armature bracket to secure the armature 14 of the contactor between the extensions. Extensions at the upper end of the armature bracket 12 are fixed to a contact actuating arm or support 15 by means of screws 16. The contact actuating arm 15 has extending wall portions 15' which mate with wall portions 17 of the contact support means 6. The mating wall portions 15' and 17 increase the arc path between contacts.

When the coil 9 is energized, it causes the armature 14 to pick up and thus transmit motion through the parallelogram linkage to the contact actuating arm 15. The contact assemblies 18 are actuated by the contact actuating arm 15 and thus the movable contacts of the contact assemblies 18 either bridge the fixed contacts supported by the contact support means 6 or open the circuit between the fixed contacts. The contact assembly is shown and described in more detail in a copending application of the same inventor entitled "Electromagnetic Contactor," filed herewith and assigned to the same assignee. The coil 9 is held in position on the center leg of the E-shaped electromagnet by means of spring

65

70

members 19 fixed to the electromagnet bracket 8 on the sides of the electromagnet. The spring members 19 are fixed in such a manner that they may be rotated out of contact with the coil 9 to allow easy removal of the coil.

Figs. 3, 4, and 5 show the detail of how the armature 14 is fixed to the armature bracket 12. The armature 14 is provided with spacer members 20 along its outer surfaces and the armature bracket 12 is provided with spacer members 21. The spacer members 20 are in the shape of segments of a sphere and the spacer members 21 are shaped as matching segmental spherical sockets for the members 20.

The bolt 13 passes through the extensions on armature bracket 12, the armature 14 and the spacer members 20 and 21. Thus, it is seen the armature can move about any axis intersecting the theoretical center of the sphere of which spacer members 20 are segments within the limits imposed by the clearance to the mounting bolt 13. In practice, the nut on bolt 13 is tightened just enough that there is considerable friction at the spherical joint. Thus the coil of the electromagnetic contactor is energized several times to bring the faces of the armature 14 into contact with the faces of the electromagnet and the pole faces align themselves and the load is applied at the center of the ball or sphere which in turn gives a balanced load condition. Since considerable friction is involved in the area of contact at the spherical contact surfaces, there will be no relative movement of the armature 14 and the armature bracket 12 after the pole faces have been aligned. As a consequence, the armature pole faces are held in alignment with the magnet pole faces regardless of whether the device is sealed, open, or in transition. After the original pole face alignment, the nut on the mounting bolt 13 is tightened, thus increasing the frictional force in the joint which insures there will be no movement in the armature mounting joint and consequently the resulting wear in the joint is eliminated and also wear of the pole faces due to misalignment.

The parallelogram arrangement may be seen more clearly in Figs. 6, 7, and 8 wherein the armature bracket 12 mounts on two identical rocker arms 10 and 11. The bearing formed at the junction of the rocker arms 10 and 11 and the armature bracket 12 are of the knife-edge type. The opposite ends of the two rocker arms 10 and 11 are mounted on the bearing bracket 7 and the bearing formed by the junction of the rocker arms 10 and 11 with the bearing bracket 7 is also of the knife-edge type. The bearing formed by the junction of the upper rocker arm 10 with the bearing bracket 7 and the bearings formed by the upper rocker arm 10 and the lower rocker arm 11 with the armature bracket 12 are spring loaded by small compression springs 22 which are identical. The two springs 23 at the bearing formed by the junction of the lower rocker arm 11 with the bearing bracket 7 perform the dual function of keeping the bearing spring loaded and also providing a torque couple at the bearing to provide a positive return force for the armature 14 when the electromagnetic coil 9 is deenergized. The two rocker arms are shown as identical to simplify the manufacture but it will be noted that they are not used in exactly the same manner and, therefore, are not necessarily identical.

It will be recognized that the objects of the invention have been achieved by providing an electromagnetic contactor whereby a single electromagnet is employed to control the opening or closing of a plurality of circuits by means of the operation of switches and contacts. In addition, the electromagnetic contactor provides that the load will be applied to the armature along an axis perpendicular to the plane of the pole faces and substantially through the theoretical center area of all pole faces resulting in a minimum of wear both on the pole faces and also in the armature mounting joint.

While in accordance with the Patent Statutes, one best known embodiment of the invention has been illustrated and described in detail, it is to be particularly understood

that the invention is not limited thereto or thereby but that the inventive scope clearly includes equivalents.

I claim as my invention:

1. A quadrilateral mechanical linkage comprising, a first and a second plate, said first and second plates having lateral slots in each end, a third and a fourth plate, said third plate having end portions which extend into one pair of lateral slots on said first and said second plates, said fourth plate having end portions which extend into the remaining pair of lateral slots in said first and second plates, said plates forming a parallelogram arrangement, resilient biasing means at each corner of said parallelogram arrangement to cause the four plates to forcibly engage each other, the line of action of the force of said biasing means for at least one corner of said parallelogram being displaced from the plane of the laterally slotted plate thereat giving a torque couple.
2. An electromagnetic device comprising, a base plate, a bearing bracket fixed to said base plate and having bearing surfaces at opposite ends, two rocker arms, each rocker arm having the bearing edge at one end engaging bearing surfaces at the opposite ends of said bearing bracket, an armature bracket, said armature bracket having bearing surfaces at either end engaged by the remaining bearing edges of said rocker arms in such a manner that said armature bracket, said rocker arms, and said bearing bracket form a parallelogram with the planes of said rocker arms substantially parallel, the first of said rocker arms having first and second helical springs in coaxial alignment with each other and substantially aligned with the longitudinal center line of said first rocker arm, one helical spring at either end biasing the bearing edges of said first rocker arm against the bearing surfaces of said armature bracket and said bearing bracket, said second rocker arm having extensions in a plane perpendicular to the plane of the rocker arm and displaced from the plane of the bearing bracket, a third helical spring having its axis substantially in the plane of the second rocker arm and in substantial coincidence with the longitudinal center line thereof, said third helical spring biasing the bearing edges at the end of said second rocker arm engaged by said third helical spring against the bearing surface of said armature bracket, fourth and fifth helical springs having their axes in a plane substantially parallel to but removed from the plane of said second rocker arm, each of said fourth and fifth helical springs engaging one of said extensions and the bearing bracket to bias the bearing edges of the second rocker arm against the bearing surfaces of the bearing bracket and give a torque couple at the bearing, a magnetic core member fixed to said base plate within the area defined by said parallelogram, coil means on said magnetic core member for producing a magnetic flux in said magnetic core member, and an armature member within the area defined by said parallelogram secured to said armature bracket and positioned to be linked and moved by the flux of said magnetic core member toward said magnetic core member in a direction at substantially right angles to the planes of said rocker arms, to correspondingly move said armature bracket.
3. An electromagnetic device comprising, a base plate, a first and a second plate, said first and second plates having lateral slots in each end, a third and a fourth plate, said third plate having end portions which extend into one pair of lateral slots on said first and said second plates, said fourth plate having end portions which extend into the remaining pair of lateral slots in said first and second plates, said plates forming a parallelogram arrangement with said third and fourth plates in substantially parallel planes, resilient biasing means at each corner of said parallelogram arrangement to cause the four plates to forcibly engage each other, the line of action of the force of said biasing means for at least one corner of said parallelogram being displaced from the plane of the laterally slotted plate thereat giving a torque couple, said fourth plate being fixed to said base plate, a magnetic core mem-

ber mounted on said fourth plate positioned within the area defined by said parallelogram, a coil mounted on said core member for producing magnetic flux therein when energized, and an armature member positioned within the area defined by said parallelogram mounted on said third plate and attracted by the flux of said core member toward said core member along a path at substantially right angles to the planes of said first and second plates to thus move said third plate.

4. A quadrilateral mechanical linkage comprising, a bearing bracket, two rocker arms in substantially parallel planes, each rocker arm having a bearing edge at one end engaging bearing surfaces at the opposite ends of said bearing bracket, an armature bracket, said armature bracket having bearing surfaces at either end engaged by said rocker arms in such a manner that said armature bracket, said rocker arms, and said bearing bracket form a parallelogram for any position of said armature bracket with respect to said bearing bracket, the first of said rocker arms having helical springs in coaxial alignment with each other, one at either end and substantially on the longitudinal center line of said first rocker arm, biasing the bearing edges of said first rocker arm against the associated bearing surfaces on said armature bracket and said bearing bracket, said second rocker arm having extensions in a plane substantially perpendicular to the plane of the second rocker arm and displaced from the plane of the bearing bracket, a third helical spring having its axis in substantially the plane of the second rocker arm and in substantial coincidence with the longitudinal center line of the second rocker arm, said third helical spring biasing the bearing edges at the end of said second rocker arm engaged by said third helical spring against the bearing surface of said armature bracket; fourth and fifth helical springs having their axes in a plane substantially parallel to but displaced from the plane of said second rocker arm, each of said fourth and fifth helical springs engaging one of said extensions and the bearing bracket to bias the bearing edges of the second rocker arm against the bearing surfaces of the bearing bracket and give a torque couple at the stated bearing point.

5. An electromagnetic device comprising, a base plate, a bearing bracket fixed to said base plate, two rocker arms in substantially parallel planes, each rocker arm having a bearing edge at each end, respective rocker arm bearing edges on corresponding rocker arm ends engaging respective bearing surfaces at the opposite ends of said bearing bracket, an armature bracket, said armature bracket having respective bearing surfaces at either end engaged by respective bearing edges on the remaining ends of said rocker arms in such a manner that said armature bracket, said rocker arms, and said bearing bracket form a parallelogram for any position of said armature bracket with respect to said bearing bracket, the first of said rocker arms having first and second helical springs in coaxial alignment with each other, one at either end of said first rocker arm and substantially on the longitudinal center line of said first rocker arm, said helical springs respectively biasing the bearing edges of said first rocker arm against the associated bearing surfaces of said armature bracket and said bearing bracket, the second rocker arm having a pair of laterally displaced extensions in a plane perpendicular to the plane of the second rocker arm and displaced from the plane of the bearing bracket, a third helical spring having its axis substantially in the plane of the second rocker arm and in substantial coincidence with the longitudinal center line of the second rocker arm, said third helical spring biasing the bearing edges at the end of said second rocker arm engaged by said third helical spring against the associated bearing surface of said armature bracket; fourth and fifth helical springs having their axes in a plane substantially parallel to but displaced from the plane of said second rocker arm, each of said fourth and fifth helical springs engaging one of said extensions and the bearing bracket to bias the

5 bearing edges of the second rocker arm against the bearing surfaces of the bearing bracket and give a torque couple at the bearing, an E-shaped magnetic core member within the area defined by said parallelogram fixed to said base plate and having pole faces, coil means mounted on said core member to produce magnetic flux in said core member when energized, and an armature member within the area defined by said parallelogram mounted on said armature bracket and having faces to match the pole faces of said E-shaped magnetic core member and positioned to be linked by the flux of said E-shaped magnetic core member and thus be magnetically attracted toward said core along a path substantially at right angles to said rocker arms.

10 15 20 25 30 35 40 45 50 55 60 65

6. An electromagnetic device comprising, a support; first, second, third and fourth plates arranged to form a parallelogram; each of said plates having each of its ends bearing against a different plate; resilient biasing means at each corner of said parallelogram arrangement to cause the four plates to forcibly engage each other and said biasing means for at least one corner of said parallelogram giving a torque couple; said first plate being fixed to said support, an E-shaped magnetic core member within the area defined by said parallelogram mounted on said first plate and having pole faces; armature means within the area defined by said parallelogram having pole faces to match the pole faces of said E-shaped magnetic core member; means mounting said armature means on said second plate with the pole faces thereof normally spaced from the pole faces of said E-shaped core member along a path substantially at right angles to the plane of one of the remaining plates, said second plate being opposite said first plate; said third and fourth plates at all times lying in substantially parallel planes; said armature means being linked by the flux of said core member and attracted toward said core member upon energization of said coil.

7. An electromagnetic device comprising, a fixed core having a coil thereon and a movable armature, said fixed core and said movable armature being formed of a plurality of punchings and having matching pole faces, said armature having a laterally disposed hole therethrough extending through opposite armature side faces; a pair of members, one mounted on each of said side faces and each having a convex spherical surface an axis of which is aligned with the axis of said hole, the center of curvature of each spherical face being substantially at the longitudinal center of said hole, a movable support for said movable armature mounting said armature with the pole faces thereof normally spaced from and confronting the pole faces of said core to be linked and moved by the flux of said core toward said core when said coil is energized, said movable support having a pair of legs straddling the lateral dimension of said armature, each leg having a spherical socket receiving the corresponding one of said spherical faces in frictional contact relation, said legs and said member having holes therethrough substantially aligned with the hole through said armature when said pole faces are engaged, a tension rod of smaller cross-sectional dimension than said holes clearing through said holes and clamping the mating surfaces of said spherical faces and sockets in frictional engagement to maintain the position between the armature and said support established by engagement of said pole faces.
